(57) **CLAIM**

The ornamental design for a pulse oximeter, as shown and described.

DESCRIPTION

FIG. 1 is a top, right, front perspective view of a pulse oximeter showing the new design;

FIG. 2 is a bottom, back, left perspective view thereof;

FIG. 3 is a front view thereof;

FIG. 4 is a back view thereof;

FIG. 5 is a side view thereof;

FIG. 6 is another side view thereof;

FIG. 7 is a top view thereof; and,

FIG. 8 is a bottom view thereof.

The broken lines illustrate portions of the pulse oximeter that form no part of the claimed design. The broken lines form no part of the claimed design.
